WARNER R. BUXTON, OF LONGMEADOW, MASSACHUSETTS.

FLEXIBLE POCKET RECEPTACLE.

Application filed September 16, 1925. Serial No. 56,771.

This invention relates to improvements in flexible pocket receptacles and, more especially, to receptacles adapted to carry coins, although the invention is naturally capable 5 of other and more general uses.

Considering the invention in connection with one of its preferred uses, such as a coin purse, the receptacle of this invention affords a pocket and a tray foldably connected 10 therewith, so that the tray can be superposed on the pocket portion of the receptacle to close the pocket or can be moved to lie in extended relation therewith, in such a fashion that the contents of the pocket may gravitate 15 into the tray and become conveniently accessible. In the case of coins, the latter spread out, when slid from the pocket into the tray, so that selection of the desired coins is facilitated. The tray has side and end 20 wings to prevent the escape of the contents.

There are many examples of coin purses of this general type in the prior art. They are of two general types. In one type, the wings of the tray are built up, with leather and 25 even metal reinforcements, to form a thick wall around the margins of the tray to prevent the coins from sliding out. This sort of a wall seldom is high enough to prevent escape of coins under all conditions and, 30 in any event, results in a heavy bulky purse which crowds and bulges the pocket and is uncomfortable to carry. In the other type, the purse is thin and flat, when closed, which is the condition desired here. The difficulties 35 with this latter type of purse are of two general kinds. First, the wings of the tray are too low to adequately perform their intended function under all conditions and, second, the pocket either does not readily 40 spread open to the desired degree or, if it does, then it does not spread open in an insured regular and controlled way. Moreover, in all thin, flat coin purses, of which I am aware, there is a stitched seam along the 45 side edges of the pocket and the wings of the tray, which seam is much stiffer and less flexible than the top and bottom walls of the purse. The result is that when the sides of the purse are squeezed together, the top and bottom walls of the coin pocket will be 50 the first to yield and they will buckle in a haphazard way, both walls remaining in contact, or substantially so, and without any tendency to spread the walls apart. In one prior art purse, the top and bottom walls 55 have been creased in an attempt to get the

spreading effect under the conditions described but a full, wide and adequate spread is not effected and the walls adjacent the sides of the pocket remain nearly in contact 60 leaving sharp V-shaped places near the margins wherein coins may catch and become wedged in.

The flexible receptacle of this invention starts with the flat, thin purse of the prior 65 art and eliminates the stitched seam at the side edges, providing in its place a connection between the two superposed walls of the pocket and the wings and floor of the tray, which is preferably even more flexible 70 than the material out of which the walls are made. Then, these walls are suitably constructed, as by creasing or in other ways, to bend along definite predetermined lines which extend from the corners of the receptacle inwardly at an inclination to the side edges. The result is the reverse of a 75 "bellows fold" in that the parts of the fold extend outwardly rather than inwardly. A full, substantial spreading of the walls occurs in a definite and controlled manner and, aside from the spreading of the walls of the pocket, the wings of the tray are elevated from a position, wherein they lie very 80 nearly flatly against the floor of the tray, into a position in which they stand up to a substantial extent sufficient for their intended purpose. An ordinary bellows fold does not permit a thin flat purse when 85 closed. It does permit, but does not effect, the spreading of the walls. These walls have to be pulled apart. In the present case, by having the elements of the bellows fold project outwardly rather than inwardly with 90 respect to the pocket, the purse is kept thin and flat, when closed, and these elements are accessible to be used as the means for spreading the walls when the sides of the purse are squeezed together.

There are many details contributing to 100 the broad object of the invention as above expressed by a description of its aims and purposes. These and other objects will appear in the following description and will be pointed out in the appended claims.

The invention will be disclosed with reference to the accompanying drawings, in which:

Fig. 1 is a plan view of the blank from 110 which one form of a pocket receptacle, embodying the invention, may be made;

Figs. 2, 3 and 4 are top plan, bottom plan,

and side elevational views, respectively, of the finished pocket receptacle, shown as opened but not spread;

Figs. 5 and 6 are side elevational and top plan views, respectively, of the receptacle when spread by pressing together its side walls near the ends of the central transverse line of fold thereof;

Fig. 7 is a cross sectional view taken on the line 7—7 of Fig. 6;

Fig. 8 is a side elevational view of the receptacle, when closed;

Figs. 9, 10 and 11 are plan views of the several blanks from which a second form of pocket receptacle is made;

Fig. 12 is a top plan view of such receptacle, shown as opened but not spread;

Fig. 13 is a side elevational view showing the receptacle of Fig. 12 as opened and spread;

Fig. 14 is a cross sectional view showing the receptacle as opened and spread;

Fig. 15 is a top plan view of a third form of pocket receptacle, shown as opened but not spread; and

Figs. 16 and 17 are side elevational and top plan views, respectively, of the third form of receptacle, shown as opened and spread.

Referring first to Figs. 1 to 8 inclusive, which show the first and simplest form of the invention, the pocket receptacle there shown is intended for a coin purse and is of the so-called tray purse type. It is made up from a single blank or piece of leather, or other suitable flexible material, which is cut out in the form shown in Fig. 1 and scored along the transverse lines 20 and along the longitudinal lines 21. These lines 20 and 21 define the ends and sides of the finished purse and their intersections define the corners of the finished purse. The lines 21 divide the blank into a relatively wide central portion and two side portions which are about half the width of the central portion and located one on each side thereof. The leather piece is also suitably creased along lines 22, 23 and 24, and cut out in its side edges, as at 25. These lines 22, 23 and 24 extend from said corners inwardly in divergent relation with the adjacent lines 21. The two creases 22, adjacent each score line 21, intersect centrally between the ends of the leather piece and the lines 23 and 24 terminate at the corners of the cut out portions 25.

The two side portions of the blank are then folded along the scored lines 21, being brought upwardly and then carried downwardly and superposed upon the central portion of the blank. The edges 26 are then joined together in the manner best shown in Fig. 7 with a stitched seam 27. These edge portions, instead of being overlapped, are upturned. That is, after the blank has been

folded into tubular form, and before the ends of the tube have been closed, the two side portions to be joined along their edges 26 are laid flatly one upon the other and stitched together in the ordinary manner. This leaves the edges 26 upturned, when the tube is later flattened down as shown in Fig. 2. The seam is usually ironed down so that it projects only slightly above the adjacent walls. The tubular article, thus formed and flattened down, is then held permanently in flattened down condition by folding over end flap portions 28, formed on the central portion of the blank beyond lines 20, and securing these flaps, as by adhesive, to the ends of the joined side portions which were folded over upon the central portion of the blank. The ends of the receptacle are thus closed and the only opening into the receptacle is that formed by the combined cut out portions 25.

The receptacle, thus formed, is a tray purse having a pocket 30 and a tray 31, the latter being bordered by marginal side and end wings 32 and 33, respectively. The tray communicates with the open mouth of pocket 30, when the purse is opened as shown in Figs. 2 to 6, and functions to close the otherwise open mouth of the pocket, when the tray section of the purse is folded, along a central transverse line indicated at 34, over upon the pocket section, as shown in Fig. 8. The two sections of the purse may be fastened together by interengageable fasteners 35, one of which is fixed to a flap 36 secured to one section and the other of which is riveted to the other section.

It will be noted that the back wall of pocket 30 and the floor of tray 31, are each made up of a central shovel-shaped or trapezoidal portion 37 and two oppositely located right-triangular portions 38. The portions making up the back wall of the pocket are oppositely disposed to those making up the floor of the tray so that the bases of the triangular portions and the short parallel sides of the trapezoidal portions all coincide in the common line of fold 34. The apices of the triangular portions 38 are at the corners of the purse. The front wall of pocket 30 is similarly formed with a trapezoidal portion 39 and two right triangular portions 40. These triangular portions 38 and 40 function to separate the front and back walls of the pocket 30; to depress the floor of the tray; and to elevate the wings thereof. This is effected by squeezing the sides of the open purse together near the ends of the fold line 34. The squeezing can readily be effected with the thumb and finger of one hand while the purse is held therebetween. The result is the swinging of all the right-triangular portions, about the hypotenuse of each through an angle of about 90 degrees, thereby moving these por-

tions from their normal positions, in which they lie substantially in the same plane with the trapezoidal portion to which they are connected, to positions in which they lie substantially at right angles thereto. The triangular portions 38 and 40 swing into or at least closely approach a common plane, as indicated in Fig. 7 and the result is a full and wide spreading apart of the walls of the pocket and a depression of the floor of the tray, all in a regular, systematic manner and according to a predetermined plan. Naturally also, the side wings 32 of the tray rise with the portions 40 to which they are connected. At the line of connection, the wings 32 become vertical, or substantially so, and the lifting movement is communicated along the side wings to the end wing 33, although the latter does not rise quite so high as do the side wings at their lines of junction with portions 40.

The same results, as to spreading of the walls of the purse, depression of the floor of the tray and elevation of the wings of the tray, can be effected in other ways, and still make use of the same principles which permit the action above described. The creasing of the leather piece along the lines 22, 23 and 24 is merely one suitable means for causing the walls of the pocket receptacle to bend in the described manner when squeezed. Any other suitable means which will cause the walls to bend along these lines may be used. For example, in Fig. 12, a trapezoidal piece 41 may be applied to one wall of the pocket 30' there shown. This makes the central portion of such wall stiffer than the triangular marginal portions and the result is that the triangular marginal portions will rise in the same manner as the portions 40. Likewise, by applying a rectangular stiffening piece, such as 42, to the floor or tray 31', the marginal portions of the floor will elevate, when the sides of the purse are squeezed, while the reenforced area remains unbent. If the marginal portions of the floor bend into substantially vertical positions, so will the corresponding portions of the back wall of pocket 30'. Also the wings 32' and 33' will be carried up with the triangular marginal portions of the front wall of the purse. The creasing is thus not essential in all cases.

It should also be pointed out that the purse is restrained, by the bracing action of the joined ends, from bending readily at that location. Consequently, if one or more walls of the purse are reenforced or stiffened near the line of fold 34 but intermediate the ends of this line, leaving marginal portions on opposite sides which are free to bend, the functions above described will be effected. That is, there will be definite lines of bending extending in a straight line from the ends of the reinforcement to the corners of

the purse. It will thus be seen that the entire area of the trapezoidal portion 41, or the reenforcement 42, is not necessary for all purposes, notwithstanding that they are desirable in that the action described is made more definite and certain. It is the portions of the reinforcements located near the line of fold 34, which are really essential where reenforcement, rather than creasing or scoring, is relied upon to make the bending occur repeatedly in a regular and planned manner.

In Figs. 12 and 14, I have shown a reenforcement in channel form caused by a flap 43 formed on the trapezoidal piece 41 and bent backwardly thereupon over the top wall of pocket 30'. When the stiffening piece is of leather or the like, the channel effect at the point described is very desirable on account of the increased stiffness secured. As shown, the reenforcement of the channel shaped and the trapezoidal shaped stiffeners are combined to secure ideal functioning although, obviously, they need not be for all purposes.

The parts 41 and 43, as shown, are made as one piece and are inserted as a loose-piece lining for the upper wall of pocket 30'. By turning down flap 43, cards or the like can be inserted between the upper wall of pocket 30' and member 41, so that the pocket is partitioned by this member as an incident to its primary reenforcing function. Also the flap, as 36', may be formed as a part of member 41 and passed out of pocket 30' through a slit in its end, thereby tending to hold the member 41 in place. By preference, the sides of the flap 43 diverge from their line of junction with member 41 or otherwise project beyond the ends of said line. Thus, when flap 43 is turned down to secure access to the auxiliary pocket, provided by it, the flap then overlies the wings 32' of tray 31' and cannot readily get into the tray. This eliminates the otherwise possible chance of coins sliding from the tray into the auxiliary pocket, when the flap is turned down and also insures that the flap is readily accessible. This flap is folded down or creased so that it has a natural tendency to stay in the position illustrated.

When it is desired to carry bills as well as coins in the purse, I apply over the back of the purse a piece 44 which is cut out from a blank of leather or the like in the form shown in Fig. 10. As may be seen from comparison of Figs. 9 and 10, this blank is somewhat longer than the purse to provide slack as shown in Fig. 13. The blank is provided with side and end flaps 45 and 46, respectively, which are folded over upon and secured by adhesive to the top walls of the purse, the side flaps at least being skived down, so as not to materially detract from the freely flexible side edge connection 21'. 130

The piece 44, in that edge which is secured to the side edge of the purse, is cut away at its center, as at 47, to compensate for the slack above described.

5 By the addition of the slack piece 44, I am enabled to increase the depression of the bottom wall of the pocket 30' and the depression of the floor of tray 31'. Particularly, I am able to get a greater depression 10 near the closed end of the pocket and near the closed end of the tray. The piece 44, therefore, has a real purpose in addition to its usual and obvious purpose. For example, I construct the purse from the blank 15 shown in Fig. 9, scored longitudinally at 21' to form a central section, which constitutes the floor 48 of the tray and the bottom wall 49 of the pocket. The side sections are folded and fastened in the manner above described but the leather is not creased along lines such as 22, 23 and 24, as formerly. Also, no end flaps 28 are provided and I use the flaps 46 of piece 44 in their place. Since such a means is available for closing 25 the ends of the purse, I can then cut back the ends of the central portion of the blank, as shown at 50, leaving end edges 51 which are materially spaced from the corresponding ends of the purse, as will be seen in 30 Figs. 13 and 14. Therefore, the former restriction of the bottom wall of the pocket and floor of the tray at their ends, by reason of their connection with the top wall, is done away with and these ends can and do depress 35 to a substantial degree as will appear from Figs. 13 and 14. The piece 40 also serves as a limiting means for determining the extent of depression of the parts 48 and 49, which, when sufficiently depressed, take 40 up all the slack in the piece 44.

The invention is not confined to a coin purse and may be used generally for various purposes. With only slight modifications and increase in dimensions, the pocket receptacle will serve admirably as a tobacco pouch. The tobacco is normally contained in the pocket portion of the receptacle but, when the latter is opened and squeezed as described, the tobacco will slide into the tray portion. The pipe may then be inserted through the opening in the tray and there filled. For this purpose, it is desirable to have the receptacle remain in its spread or squeezed condition without effort on the part 55 of the operator.

Such an embodiment of the invention is shown in Figs. 15 to 17. The receptacle there shown is constructed in the same general manner and makes use of exactly the 60 same principles as the receptacle shown in Figs. 1 to 8, inclusive. It differs in that it is larger and in that each pair of corresponding inclined creases 22" and the corresponding pair of creases 23" converge much more rapidly and result in corresponding

right-triangular portions of greater area, designated 38" and 40". Also, the opening 52 into the tray is made smaller, relatively to the area of the tray than formerly, and approximately round in shape. This results 70 in higher wings 32" and 33" for the tray. Otherwise, the construction is substantially the same and will be readily understood without further description, because all parts in Figs. 15 to 17, which correspond to 75 parts shown in Figs. 1 to 8, have been designated by the same numerals, double primed.

This receptacle is made so that it will remain in the open and spread position shown in Figs. 16 and 17. To effect this result, 80 the various parts of the receptacle are so constructed and arranged that the normal squeezing action, utilized to spread the receptacle as described, will carry the shorter leg of each right triangular portion 38" 85 not only into the same plane with the corresponding leg of the adjacent portion 40", as indicated by the lines 55 and 56 in Fig. 17, but slightly beyond this position, as indicated by the lines 55' and 56' in Fig. 17. 90 The action is something like a toggle in that the parts 38" and 40" are carried beyond any position, in which they would tend, when released, to resume their normal 95 positions. The lines 55' and 56' can be considered as analogous to toggle links and it will be seen from Fig. 17 that they have "crossed centers." Any substantial movement of the lines 55' and 56' beyond the locking position is resisted because the parts 100 38" and 40" would have to fold inwardly like an ordinary bellows fold to permit the action. The toggle hold is broken by pressing the top and bottom walls of the purse together. Of course, this would not break 105 a toggle with rigid links but the analogous parts in this receptacle are flexible. Such parts start to bend from both top and bottom, when the described pressure is applied, until sufficient tension is created to snap the 110 central portions out of their inwardly buckled and locking positions.

When the right triangular portions 38" and 40" are made as large in area as shown in Figs. 15 to 17, it is generally desirable to 115 reinforce them by a strip 57 applied to their inner walls adjacent the short legs of these portions. This may not be necessary with the stiffer leathers but it is desirable with the more flexible ones to add stiffness, hold 120 the parts in shape and insure that they will repeatedly function in the planned manner.

The operation of the receptacle will be largely obvious from the foregoing description and need be but briefly described. The 125 receptacle, closed as in Fig. 8, is opened by releasing the fasteners 35 and swinging the tray section into extended relation with the pocket section, as shown in Fig. 2. The open receptacle is usually held in one hand 130

between the thumb and one or more fingers so that its side edges can be conveniently pressed together and so that the receptacle can be tilted, if necessary, to cause the con-

5 tents of the pocket 30 to slide out into tray 31. By pressing the side edges of the receptacle adjacent the ends of the lines of fold 34, the sections 38 and 40 are caused to swing into, or closely approach, a common 10 plane and due to their triangular configuration cause the bottom of the pocket and the floor of the tray to be depressed and the top of the pocket and the wings of the tray to be elevated.

15 In all three forms of the invention, the described action is effected in the same general way, differing only in the particular means by which the walls of the receptacle are biased to bend readily along definite and 20 natural lines which permit the spreading of the walls of the coin pocket in the same general and effective manner as a spreading is obtained in a bellows fold pocket book but with the following distinctions. The pocket 25 is not constricted in capacity by the presence of the bellows fold elements therein. It is kept thin and flat, when closed, for the same reason. Also, by placing the bellows fold elements in the manner disclosed, they 30 are accessible for use, by the described squeezing action, as the means for causing the spreading of the walls, as distinguished from merely being permissive of the spreading. Moreover, the spreading action on the 35 pocket is coupled with a depression of the floor of the tray and a substantial elevation of the wings thereof.

As a consequence, the receptacle can be 40 made very thin and nearly flat, when closed, and yet a wider, more adequate and more satisfactory opening of the pocket can be effected in a simple and convenient manner than in any prior art purse, with which I am familiar. Coupled with the spreading 45 of the walls of the pocket is a substantial depression of the floor of the tray combined with an elevation of the wings thereof, whereby an adequate marginal wall for the tray is provided, at times when needed, 50 without interfering with the desired flat, thin character of the purse when closed.

The invention has been disclosed herein for illustrative purposes but the scope of the invention is defined by the appended claims 55 rather than by the foregoing description.

What I claim is:

1. A pocket receptacle, comprising, a casing made up of flexible material in the form of a flattened down tube, means for closing 60 the ends of the latter, said casing affording a pocket and a winged tray formed as an extension of the mouth of the pocket and adapted to be folded over upon the pocket to close the latter, both walls of said casing being constructed to bend along prede-

termined lines, which extend one from each corner of the casing inwardly at an acute angle with the adjacent side edge of the casing.

2. A pocket receptacle, comprising, a casing made up of flexible material in the form of a flattened down tube, means for closing the ends of the latter, said casing affording a pocket and a winged tray formed as an extension of the mouth of the pocket, and 70 adapted to be folded over upon the pocket to close the latter, and a reenforcement covering part of one wall of said pocket and having its side edges extending at an acute angle to the adjacent side edges of the pocket 75 and converging toward the mouth of the pocket.

3. A pocket receptacle, comprising, a casing made up of flexible material in the form of a flattened down tube, means for closing 80 the ends of the latter, said casing affording a pocket and a winged tray formed as an extension of the mouth of the pocket and adapted to be folded over upon the pocket to 85 close the latter, and a reenforcement covering part of one wall of said pocket, and extending across the same with its ends in spaced relation with the adjacent side edges 90 of the pocket.

4. A pocket receptacle, comprising, a casing made up of flexible material in the form of a flattened down tube, means for closing the ends of the latter, said casing affording a pocket and a winged tray formed as an extension of the mouth of the pocket and 95 adapted to be folded over upon the pocket to close the latter, and a reenforcement applied to the top wall of said pocket and extending across the same with its ends in spaced relation with the adjacent side edges 100 of the pocket, said reenforcement being channel shaped in cross section to fit over 105 said wall at the mouth of said pocket.

5. A pocket receptacle, comprising, a casing of oblong shape made up of flexible material in the form of a flattened down tube, means for closing the ends of the casing and tending to hold the two walls thereof against transverse bending at its ends, said casing being foldable along a transverse line intermediate its ends so that one section thereof can be swung from an open position over upon the other section into a closed position in which one part of one wall lies substantially contiguous with the other part, one of 110 said parts of said wall being cut away except for marginal portions along the sides and the closed end leaving an opening normally closed by the other part when the casing is in closed position, both walls of said 115 casing being constructed with a tendency to bend along predetermined lines when the sides of the open casing are squeezed together near said transverse line, said predetermined lines leading from the corners of 120 125 130

the casing at each end and extending inwardly at acute angles with the adjacent sides of the casing.

6. A pocket receptacle, comprising, a casing of oblong shape made up of flexible material in the form of a flattened down tube, means for closing the ends of the casing and tending to hold the two walls thereof against transverse bending at its ends, said casing being foldable along a transverse line intermediate its ends so that one section thereof can be swung from an open position over upon the other section into a closed position in which one part of one wall lies substantially contiguous with the other part, one of said parts of said wall being cut away except for marginal portions along the sides and the closed end leaving an opening normally closed by the other part when the casing is in closed position, and means for causing the walls of said casing to bend along definite lines when the sides of the open casing are squeezed together near said transverse line, said definite lines extending from the corners of the casing at each end and extending inwardly at acute angles with the adjacent sides of the casing.

7. A pocket receptacle, comprising, a casing having substantially square ends and made up in the form of a flattened tube from flexible material, the edges of which are joined together by a longitudinal seam, means for closing each end of the casing and arranged to stiffen such ends to resist transverse bending, the latter adapted to be folded along a transverse line intermediate such ends so that one section may be superposed upon the other with their inner walls in substantially contiguous relation, one of said sections having its inner face cut away except for marginal portions along opposite side edges and one closed end, whereby a winged tray is formed by the last named section and a pocket is formed by the other section adapted for communication with the tray, said seam extending longitudinally of the casing and intermediate its side edges.

8. A pocket receptacle, comprising, a casing having substantially square ends and

made up in the form of a flattened tube from flexible material, the edges of which are joined together by a longitudinal seam, means for closing each end of the casing and arranged to stiffen such ends to resist transverse bending, the latter adapted to be folded along a transverse line intermediate such ends so that one section may be superposed upon the other with the inner walls thereof in substantially contiguous relation, one of said sections having its inner face cut away except for marginal portions along opposite side edges and one closed end, whereby a winged tray is formed by the last named section and a pocket is formed by the other section adapted for communication with the tray, said seam extending longitudinally of the inner face of said pocket intermediate its side edges from the closed to the open end thereof and also extending across that marginal portion which is disposed along said end and substantially at right angles thereto.

9. A flexible pocket receptacle, comprising, a casing made up from flexible material in the form of a flattened down tube with unstitched and freely flexible side edges, a strip of flexible material longer than the casing disposed adjacent one wall of the casing and secured to the other wall of the casing along one side edge and both ends thereof thereby serving to close the otherwise open ends of said casing, the first named wall terminating at its ends short of and in spaced relation with the corresponding ends of the other wall, an opening providing in the latter wall, and means for causing said walls to bend along predetermined lines when the side edges of the casing are squeezed toward one another near the center of the casing, said predetermined lines extending from the corners of the casing in inclined relation with said side edges until each line intersects another or a wall of said opening.

In testimony whereof I have affixed my signature.

WARNER R. BUXTON.
